UNITED STATES PATENT OFFICE

GEORGE A. FULLIPS, OF DETROIT, MICHIGAN

VALVE GRINDING MACHINE

Application filed September 9, 1929. Serial No. 391,469.

This invention relates to valve grinding machines, and particularly to machines for grinding a plurality of valves simultaneously.

5 An object of the invention is to provide an improved mechanism for simultaneously effecting a similar oscillatory rotation of a plurality of spindles, individually carrying valve-grinding tools.

10 Another object is to provide an improved mechanism peculiarly suited for valve grinding and imparting to a spindle a cycle of rotative oscillations varying as to degree in a predetermined manner.

15 A further object is to adapt a plurality of rotative chucks to be axially shifted either simultaneously or individually to shift tools carried thereby to or from their working positions.

20 These and various other objects the invention attains by the construction hereinafter described and illustrated in the accompanying drawings, wherein:

Fig. 1 is a front view of the improved 25 valve grinding machine.

Fig. 2 is a view of the same in side elevation.

Fig. 3 is a rear view thereof.

Fig. 4 is a horizontal sectional view through 30 the spindle-mounting head of the machine, taken on the line 4—4 of Fig. 2.

Fig. 5 is a vertical section taken upon the line 5—5 of Fig. 3 and showing primarily a gear train and means for periodically oscillating an intermediate gear of said train.

35 Fig. 6 is a sectional view of said gear train, taken upon the line 6—6 of Fig. 5.

In these views, the reference character 1 designates a hollow pedestal rising from a base 2 and surmounted by a head 3. Intermediately mounted on said pedestal and forwardly projecting therefrom is a work table 4, adapted in any desired manner for vertical adjustment. Thus a gear 4a journaled upon said work table therebeneath and meshing with a rack 4b vertically elongated on the pedestal, may be rotatively actuated to raise and lower the table.

40 At some suitable point on the base 2 is mounted a motor 5 which, through a speed-

reducing pair of gears 6 and 7 drives a shaft 8 journaled upon the rear portion of the pedestal. From said shaft another speed-reducing drive is established through a train of gears 8a to a jack shaft 9 journaled in said pedestal some distance above the shaft 8. On said jack shaft, within the pedestal, is swung the upper end of an arm 10, the lower end of which rigidly carries a stub shaft 11, journaling a gear 12 driven by a gear 13, fast on said jack shaft. The shaft 8 rigidly (and preferably integrally) carries an eccentric 14 journaling the lower end of a link 15 having its upper end journaled on the stub shaft 11. Also journaled on said eccentric and coaxial therewith is a gear 16, adjacent to which a relatively large eccentric 17 is journaled on the eccentric 14 and is rigidly connected to the gear 16 in any suitable manner, as by pins 18. An eccentric strap 19 peripherally engages the eccentric 17 and is fast upon the lower end of a connecting rod 20, pivoted at its upper end to a rack bar 21 vertically reciprocatory on the rear portion of the head 3. Journaled in said head transversely to its front and rear faces is a shaft 22 rigidly carrying a pinion 23 meshing with the rack bar 21 and rotatively oscillated by the latter.

45 On the forward end of the shaft 22 is mounted fast a pinion 24 meshing with a rack 25 formed upon the top face of a bar 26 reciprocatory end wise of the head 3 in a suitable slide guide 27 carried at the front of the head 3. Said bar further has a rack 28 on its front face for driving a plurality of pinions 29 individually fast on a row of vertical spindles 30, journaled in multiple bearings 31 forwardly projecting from the head 3 above and below said pinions.

50 From the lower portion of the head 3 a multiple bearing 32 projects forwardly to journal tubular tool holders 33, respectively telescoped receiving the lower end portions of the spindles 30 and driven by the latter through pins 34 thereon engaging in longitudinal slots 35 in the upper end portions of said tool holders. It will be noted that this drive connection affords the tool holders a limited reciprocation on the spindles without interruption of the drive.

Below the lowermost bearing 31, the spindles 30 loosely carry collars 36 between which and the tool holders 33 coiled springs 37 are compressed to exert downward pressure on said tool holders. The latter project below the bearing 32 and have their lower ends adapted in any suitable manner to carry chucks 38 mounting valve-grinding tools 39. These are engageable with any suitable work carried by the table 4, such as the valve seats 40 of an engine block 41.

Above the bearings 32 the tool holders 33 are formed with annular shoulders 42 beneath which engage ring-shaped yoke portions 43 of lever arms 44. The latter project correspondingly forwardly through openings in the front of the head 3, being journaled upon a shaft 45 horizontally mounted in said head parallel to its front face. Rigidly individually connected with the arms 44 are lever arms 46 rearwardly projecting from the shaft 45 and carrying at their rear ends screws 47, adjustable substantially vertically.

Horizontally journaled in the head 3 above the rear ends of the lever arms 46 is a shaft 48 rigidly mounting a plurality of cams 49 respectively above said arms, and in normal bearing contact with the screws 47. Said shaft is adapted to be driven from the shaft 8 through a chain 50 carried by sprocket wheels 51.

The lever arms 44 project forwardly of the yokes 43 to provide handles for raising any of said arms to elevate the engaged tool holder 33. For raising or lowering said tool holders simultaneously, a lifter bar 52 horizontally extends beneath the forward ends of the arms 44 and is vertically adjustable on the head 3. Thus said bar has in its end portions vertical slots 53 receiving pins 54 forwardly projecting from said head, and a pair of rollers 55 similarly journaled on the ends of said bar rest on eccentrics 56 terminally fast on a rock shaft 57. The latter is journaled in lugs 58 on the bearing 32 and may be rocked by a handle 59 on one of its ends to swing said eccentrics up or down to raise or lower the bar 52.

In operation of the described machine, the motor 5 when energized drives the shaft 8 several times faster than the eccentric 17. The latter tends to reciprocate the rack 21 in a harmonic motion of constant stroke. Actuation of the rack is modified, however, by the relatively rapid bodily reciprocation of the large eccentric resulting from its mounting on the small eccentric, subjecting the rack to a cycle of reciprocations, each varying in stroke. That is to say, each such cycle will comprise certain reciprocations in which the strokes of the two eccentrics supplement each other, to effect a maximum composite stroke, and others in which the eccen-

trics oppose each other to produce a minimum stroke.

The varying reciprocation of the rack bar 21 effects a corresponding oscillation of the shaft 22, and reciprocation of the rack bars 26. The latter correspondingly oscillate the spindles 30 and tool carriers, whereby the tools 39 are oscillated against the work in a manner peculiarly advantageous in removing high points on valve seats.

The individual vertical adjustability of the tool carriers 33 permits ready inspection of the work being done by any of the tools, and when one job of grinding is completed, the tools may be simultaneously raised by the bar 52, as shown in dash lines in Fig. 2, during positioning of a new piece of work on the table 4.

It will be apparent to those skilled in this art that the cycle of reciprocatory motions imparted to the connecting rod 20 is dependent upon the relative speeds of the two eccentrics 14 and 17. In other words the number of minor reciprocations of said rod which are concurrent with one major reciprocation thereof may be increased or diminished by providing a higher or lower speed drive to the smaller eccentric with relation to the drive to the larger eccentric. Thus the connecting rod may be given different reciprocatory movements suited to various different purposes by simply changing the speed ratio between the two eccentrics.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. A valve grinding machine comprising a plurality of parallel spindles, tool holders reciprocating on said spindles, means maintaining a drive from said spindles to said tool holders in all positions of reciprocation of said tool holders, means for rotatively oscillating said spindles in unison, levers individually engaging said tool holders, mechanism acting on said levers for periodically raising and lowering said tool holders, and means acting on said levers for manually concurrently raising said tool holders.

2. The combination with a main shaft and a jack shaft, of an eccentric on the main shaft, a second eccentric journaled upon the first, a drive connection from the main shaft to the jack shaft, a gear secured to the second eccentric coaxially with the first eccentric, a gear upon the jack shaft, an intermediate gear, and a mounting for the intermediate gear affording same an oscillatory motion transverse to the common plane of said shafts to compensate for the bodily travel

of the second eccentric upon the first eccentric.

3. The combination with a main shaft and a jack shaft, of an eccentric upon the main shaft, a second eccentric journaled upon the first, a drive connection from the main to the jack shaft, a gear mounted upon the jack shaft in driven engagement therewith, a gear secured to the second eccentric coaxially with the first eccentric, an arm pivoted upon the jack shaft, an intermediate gear journaled upon said arm, and a swinging link connecting said arm to the first eccentric.

4. The combination with an eccentric, a larger eccentric journaled on the first-named eccentric, a connecting rod actuable by the larger eccentric, a shaft rigidly mounting the first-named eccentric, drive means for said shaft and gears driving the large eccentric from said shaft at a relatively reduced speed.

5. A valve grinding machine comprising a plurality of parallel spindles, means for rotatively oscillating said spindles, tool holders respectively reciprocating on said spindles, means maintaining a drive from said spindles to said tool holders in all positions of reciprocation of the latter, means for automatically periodically raising and lowering said tool holders, a bar transverse and adjacent to said tool holders, manually operable means for establishing and maintaining raised or lowered positions of said bar, and a connection between each tool holder and said bar for actuating the tool holders up or down in unison with said bar.

6. A valve grinding machine comprising a plurality of parallel spindles, means for rotatively oscillating said spindles, tool holders respectively aligned with an reciprocating relative to said spindles, means maintaining a drive from said spindles to said tool holders in all positions of reciprocation of the latter, a bar transverse and adjacent to said tool holders, means mounting said bar for bodily travel in the direction of reciprocation of said tool holders, a shaft journaled parallel to said bar, means for manually rocking said shaft, eccentrics on said shaft engaging the end portions of said bar to effect its aforesaid bodily travel, and means engaging each tool holder with said bar to adapt the tool holders for retraction in unison responsive to bodily travel of said bar.

7. The combination with a main shaft and drive means therefor, of an eccentric on said shaft, a second eccentric journaled upon the first eccentric for actuation by the latter orbitally to the main shaft, a jack shaft, means driving said jack shaft from said main shaft, a train of gears establishing a drive from said jack shaft to the second eccentric, one of said gears being mounted on the second eccentric for orbital travel therewith, and a

mounting for another of said gears adapting it for movement transverse to the common center line of the main shaft and jack shaft to compensate for the orbital travel of the gear mounted upon the second eccentric.

8. The combination with a main shaft and a jack shaft and drive means for said main shaft, of an eccentric on the main shaft, a second eccentric journaled upon the first eccentric for actuation by the latter orbitally to the main shaft, a speed-reducing drive connection from said main shaft to said jack shaft, a speed-reducing drive connection from the jack shaft to the second eccentric, and means mounting an element of said drive connection for oscillation to and from the common plane of said shafts to compensate for the orbital travel of the second eccentric.

9. The combination with two eccentrics differing in diameter, the larger thereof being journaled upon the latter to turn about the central axis of the latter, a drive shaft for the smaller eccentric subjecting the larger eccentric to a travel orbital to said shaft, a gear centrally coaxial with the smaller eccentric, means rigidly connecting said gear to the larger eccentric, a second gear meshing with and driving the first-named gear, supporting means for the second gear adapting it for oscillation about the axis of the smaller eccentric, and means maintaining a drive to the second gear in all positions of its oscillation.

10. The combination with a main shaft and a jack shaft, of an eccentric on the main shaft, a drive connection from the main shaft to the jack shaft, a transmission element journaled on said eccentric for orbital actuation thereby, a gear secured to said transmission element coaxially with said eccentric, a gear upon the jack shaft, an intermediate gear and a mounting for the intermediate gear affording same an oscillatory motion transverse to the common plane of said shafts to compensate for the bodily travel of the second eccentric upon the first eccentric.

11. The combination with a main shaft and a jack shaft, of an eccentric upon the main shaft, a transmission element journaled upon said eccentric, a drive connection from the main to the jack shaft, a gear mounted upon the jack shaft in driven engagement therewith, a gear secured to the transmission element coaxially with the said eccentric, an arm pivoted upon the jack shaft, an intermediate gear journaled upon said arm, and a swinging link connecting said arm to said eccentric.

12. The combination with an eccentric, and a shaft rigidly mounting said eccentric, of a transmission element journaled on said eccentric, a connecting rod, means journaling said rod upon said transmission element, eccentrically to the axis of said eccentric, drive means for said shaft, and gears driving said

transmission element from said shaft at a relatively reduced speed.

13. A valve grinding machine comprising a plurality of tool holders, a plurality of elements each intermediately engaging one of said tool holders, means acting on said elements at one side of said tool holders for periodically raising and lowering the tool holders, means acting on said elements at the other side of the tool holders for establishing and maintaining a raised position of the tool holders, and means for maintaining an oscillatory rotative drive to the tool holders independently of their raising and lowering travel.

In testimony whereof I sign this specification.

GEORGE A. FULLIPS.
